ABSTRACT OF THE DISCLOSURE

Enzyme compositions of the type used in washing, namely, bacterial protease, bacterial amylase and mixtures thereof are prepared in the form of a dry-appearing, essentially non-dusting, flowable enzyme powder, free of gummy, sticky and lumpy characteristics and resistant to moisture.

BACKGROUND OF THE INVENTION

In recent years the use of enzymes, especially bacterial protease for pre-soak and detergent washing products has greatly increased. These enzymes are now being produced in very high potency concentrations and handling problems have developed as a result of these high potency levels. Many individuals have found these enzymes to be a source of irritation. The problem is particularly acute in the manufacture and handling of the enzymes themselves and also in the handling of the enzymes in plants where they are formulated into various types of detergent products. The problem would be greatly alleviated if it were possible to produce a dust-free enzyme product.

OBJECTS

One of the objects of the present invention is to provide dry-appearing, essentially non-dusting, flowable enzyme powders free of gummy, sticky and lumpy characteristics comprising a finely divided solid enzyme of the type used in the preparation of pre-soak and detergent washing products, namely, bacterial protease, bacterial amylase and mixtures of bacterial protease and bacterial amylase.

A further object of the invention is to provide new and improved flowable enzyme powders of the type described by the use of readily available, inexpensive, non-toxic modifying ingredients.

Another object of the invention is to provide a new and improved process for producing dry-appearing, essentially non-dusting, flowable enzyme powders of the type described. Other objects will appear hereinafter.

GENERAL STATEMENT OF THE INVENTION

In accordance with the invention a dry-appearing, essentially non-dusting, flowable enzyme powder free of gummy, sticky, and lumpy characteristics comprising a finely divided solid enzyme from the group consisting of bacterial protease, bacterial amylase and mixtures of bacterial protease and bacterial amylase with or without other ingredients, as, for example, calcium acetate monohydrate, sodium sulfite, sodium sulfate, sodium tripolyphosphate, calcium carbonate and monocalcium phosphate, is prepared by intimately mixing with said enzyme with or without said other ingredients a dust and moisture inhibiting substance in the form of petrolatum or petrolatum liquid, or mixtures of petrolatum and petrolatum liquid, in an amount sufficient to reduce the dusting characteristic and impart protection against moisture but insufficient to produce gummy, sticky and lumpy characteristics and interfere with flowability.

2

The terms "petrolatum" and "petrolatum liquid" as used herein are defined in the Merck Index, 8th edition, page 800. A preferred type of petrolatum liquid is a mineral oil having a Sayboldt viscosity of 65/75 at 100° F. (37.8° C.). The same product is available in a range of Saybolt viscosity of 48/52 to 145/155, as well as a viscosity of 180/190. Hence, a general range of viscosity is from 48 to 190. The petrolatum is a yellowish to light amber or white, semi-solid, unctuous jelly. Either or both of these types of substances and mixtures thereof are effective for the purpose of the invention. The amounts required are normally within the range of 1% to 10% of the weight of the enzymes and a preferred range is 3% to 8% by weight of the enzymes.

15 The protease of the enzymes is defined in terms of PV units per gram for bacterial protease and DV units per gram for bacterial amylase. The PV activity of the bacterial protease will usually be within the range of 15,000 to 1,000,000 PV units per gram and the potency of the bacterial amylase will usually be within the range of 30 to 100,000 DV units per gram. In some enzyme compositions the amount of bacterial amylase is not significant.

20 The dust and moisture inhibiting petrolatum and petrolatum liquid or mixtures thereof can be used to prepare non-dusting, flowable enzyme powders consisting essentially of the enzymes per se. They can also be used to prepare enzyme compositions which are essentially dry-appearing, non-dusting and flowable and contain diluents such as, for example, calcium acetate monohydrate, sodium sulfite, sodium sulfate, sodium tripolyphosphate, calcium carbonate and monocalcium phosphate. In some cases other substances can be added for special purposes.

DETAILED DESCRIPTION OF THE INVENTION

25 In preparing compositions in accordance with the invention several different methods were used as follows:

(A) Mineral oil was blended at ordinary temperatures and pressures either as such or as a fine spray with the finely divided enzyme either alone or mixed with other ingredients;

30 (B) Mineral oil was blended with a mixture of the enzyme and other ingredients, except sodium sulfate and sodium sulfite was intimately mixed with the resultant product after the mineral oil addition;

(C) Mineral oil was blended with the enzyme and other ingredients except calcium acetate and sodium sulfate and calcium acetate and sodium sulfite were intimately mixed with the resultant composition after the mineral oil addition; and

35 (D) The enzyme with or without other ingredients was prewarmed to a temperature of about 50° C. and then slowly intimately mixed with a warm solution of petrolatum or a mixture of petrolatum and petrolatum liquid which had been previously warmed to about 50° C. After all of the petrolatum or petrolatum liquid had been added, blending was continued until the mixture was uniform while allowing it to cool.

40 In some cases the mixture was ground during and after the addition of the petrolatum and/or petrolatum liquid to a desired particle size, for example, a size sufficient to pass a 325 mesh sieve.

45 In the following tables in which the quantities are given in parts by weight unless otherwise indicated, calcium acetate monohydrate is symbolized by $\text{Ca}(\text{OAc})_2$, sodium tripolyphosphate by STP, sodium sulfite by Na_2SO_3 , zinc oxide by ZnO , sodium sulfate by Na_2SO_4 , calcium carbonate by CaCO_3 and monocalcium phosphate by MCP. The method of addition is given in the last column of each table.

TABLE I

Example	Potency		Percent (w/w.)			Method of addition
	Bacterial protease, PV/gram	Bacterial amylase, DV/gram	Mineral oil	Petroleum jelly		
1	360,800	-----	3	0	A	
2	715,400	240	2	0	A	
3	700,800	230	4	0	A	
4	636,200	230	6	0	A	
5	708,100	200	0	3	D	
6	693,500	200	0	5	D	
7	708,100	200	1.5	1.5	D	
8	693,500	200	2.5	2.5	D	
9	132,300	45,940	2	0	A	
10	129,600	41,090	4	0	A	
11	126,900	40,230	6	0	A	
12	130,950	41,520	0	3	D	
13	128,250	40,660	0	5	D	
14	130,950	41,520	1.5	1.5	D	
15	128,250	40,660	2.5	2.5	D	
16	125,000	40	0	2.0	D	
17	125,000	40	0	4.0	D	
18	125,000	40	0	6.0	D	
19	125,000	40	0	8.0	D	
20	125,000	40	1	1	D	
21	125,000	40	2	2	D	
22	125,000	40	3	3	D	
23	125,000	40	4	4	D	

In Table I, the proportions of enzyme are the differences between the proportions of mineral oil and/or petroleum jelly and 100. Thus, the composition of Example 1 contains 97 parts enzyme and 3 parts mineral oil. The potency is that of the final product.

TABLE II

Example	Potency		Percent (w/w.)							Method of addition

In Table II the proportions of enzymes are the differences between the proportions of other ingredients and 100. Thus in Example 24 the total amount of calcium acetate monohydrate, zinc oxide, mineral oil and sodium sulfate was 68.75 parts leaving a difference of 31.25 parts which was the total amount of bacterial protease and bacterial amylase. Initially this mixture of bacterial protease and bacterial amylase had a potency of 400,000 PV units per gram and 240 DV units per gram. Because of the diluents present the final product had a potency of 125,000 PV units per gram and 80 DV units per gram.

It will be recognized that the enzymes per se used in the examples had different potencies. Thus in Example 33 the enzyme used was a mixture of 0.75 part protease

and 66 parts bacterial amylase-protease having a potency of 19,000 PV/gram and 90,900 DV/gram.

In Example 38 68.49 parts of a bacterial protease-amylase enzyme having a potency of 730,000 PV/gram and 240 DV/gram was used.

In Examples 42 to 54 the enzyme used had a potency of 730,000 PV/gram and 240 DV/gram.

In the examples given in Table II the use of zinc oxide is optional and does not constitute a part of this invention. This use is disclosed and claimed in my copending application Ser. No. 811,225 filed Mar. 27, 1969.

In the practice of the invention as illustrated by the examples dry-appearing, essentially non-dusting, flowable enzyme powders free of gummy, sticky and lumpy characteristics are obtained. These powders are especially useful as pre-soaks for washing and in combination with other ingredients usually employed in detergents. A typical laundry detergent, for example, will contain 10% non-ionic surfactant (e.g., Triton 100), 60% sodium tripolyphosphate, about 20% sodium sulfate and minor amounts of other additives such as carboxy methyl cellulose, optical brighteners, and the like. These detergents can be mixed with standardized enzyme compositions of the type herein described in order to give products of various enzyme potencies. Thus 0.5% by weight of a standardized enzyme composition of the type herein described containing 15,000 to 150,000 PV units per gram and 0 to 150,000

DV units per gram can be added to a standard laundry detergent to give excellent results in wash waters where the detergent-enzyme formulation is added at a concentration of 0.15% and fabrics are washed with such waters at standard conditions (wash cycle of 10 minutes at 120° F. (48.9° C.) and a rinse cycle of 5 minutes at 100° F. (37.7° C.) both at 100 agitator cycles per minute).

The invention makes it possible to overcome the problems of handling the enzymes during the manufacture of the enzymes themselves and also in the handling of the enzymes in plants where they are formulated into various types of detergent products.

The invention is hereby claimed as follows:

1. A dry-appearing, essentially non-dusting, flowable enzyme powder free of gummy, sticky and lumpy charac-

teristics consisting essentially of a finely divided solid enzyme from the group consisting of bacterial protease, bacterial amylase and mixtures of bacterial protease and bacterial amylase, intimately mixed with a dust and moisture inhibiting substance from the group consisting of petrolatum, petrolatum liquid and mixtures thereof in an amount sufficient to reduce the dusting characteristic and impart protection against moisture but insufficient to produce gummy, sticky and lumpy characteristics and interfere with flowability.

2. A composition as claimed in claim 1 in which said dust and moisture inhibiting substance is petrolatum.

3. A composition as claimed in claim 1 in which said dust and moisture inhibiting substance is petrolatum liquid.

4. A composition as claimed in claim 1 in which the percentage of said dust and moisture inhibiting substance is 1% to 10% of the weight of said enzyme.

5. A composition as claimed in claim 1 in which the percentage of said dust and moisture inhibiting substance is 3% to 8% of the weight of said enzyme.

6. A composition as claimed in claim 1 in which said petrolatum is a mineral oil having a Saybolt viscosity within the range of 48 to 190 at 100° F.

7. A composition as claimed in claim 1 in which said enzyme comprises a bacterial protease having a PV activity within the range of 15,000 to 1,000,000 PV units per gram.

8. A composition as claimed in claim 1 in which said enzyme comprises bacterial amylase having an activity of 30 to 100,000 DV units per gram.

9. A composition as claimed in claim 1 in which said enzyme is a mixture of bacterial protease and bacterial amylase, the activity of said mixture being within the range of 15,000 to 1,000,000 PV units per gram and 30 to 100,000 DV units per gram.

10. An enzyme composition as claimed in claim 1 consisting essentially of an enzyme from the group consisting of bacterial protease, bacterial amylase and mixtures of bacterial protease and bacterial amylase intimately mixed with 3% to 8% mineral oil.

11. A process of preparing a dry-appearing, essentially non-dusting, flowable enzyme powder free of gummy, sticky and lumpy characteristics which consists essentially of intimately mixing a finely divided solid enzyme from the group consisting of bacterial protease, bacterial amylase and mixtures of bacterial protease and bacterial amylase with a dust and moisture inhibiting substance from the group consisting of petrolatum, petrolatum liquid, and mixtures thereof in an amount sufficient to reduce the dusting characteristic of the resultant product in its powder state and impart protection against moisture but insufficient to interfere with flowability of said powder product.
